CONTAINER

Alfred J. Chamberlain, Lafayette, La.

Application August 17, 1936, Serial No. 96,351

3 Claims. (Cl. 229—5.5)

This invention relates in general to containers and more particularly to shipping containers of the type in which the body of the container is made up of fiber or other non-metallic material suitable for such use.

One of the principal objects of the invention is to provide a container of this character which is advantageously combined with metallic end heads, one of which is removable, whereby to adapt a fibrous body container to many uses and applications to which it would not otherwise be suitable.

Another object of the invention is to so construct the upper removable end head or cover that when the cover is secured in its applied or closed position it will not only be firmly held in place but will effectively and hermetically seal the container and accomplish this in such manner that even though the container be dropped and the interconnected portions of the cover and container distorted the seal will not be impaired.

Another object is to provide a container and cover structure wherein the cover may be repeatedly applied to and removed from the container without impairing the integrity of the structure of either or reducing their capacity to establish an hermetic seal.

A further object of the invention is to provide a container construction in which the intercrimped or interlocking formations of the end heads and the container ends are practically protected and wherein the protecting structure is utilized to facilitate rolling of the container.

A further object of the invention is to provide a construction having these advantages and capacities and which is simple in its nature, durable in use and easily and comparatively inexpensive to manufacture.

Other objects and advantages reside in certain novel features of the construction, arrangement and combination of parts which will be hereinafter more fully described and particularly pointed out in the appended claims, reference being had to the accompanying drawing forming a part of this specification, and in which:

Figure 1 is a top plan view of a container constructed in accordance with the present invention;

Figure 2 is a view thereof in elevation;

Figure 3 is a view in vertical section taken on line 3—3 of Figure 2 but showing the bendable closure lugs before they are bent into locking position;

Figure 4 is a view similar to Figure 3 showing the lugs in locking position;

Figure 5 is a view in section taken on line 5—5 of Figure 2 and illustrating one way in which the lower end head may be interconnected with the lower end of the container;

Figure 6 is a view similar to Figure 4 but showing a slightly modified structure; and

Figure 7 is a fragmentary view in elevation showing another embodiment of the invention.

Referring to the drawing, and more particularly to Figures 1 to 5, inclusive, it will be seen that in the embodiment of the invention there illustrated the container comprises a generally cylindrical body portion 1 which is constituted of fibrous material. The body may be of laminated fibrous construction or may be constituted of other non-metallic material suitable for such use.

The lower end of the body portion 1 is surrounded by and interconnected with a closely fitting reinforcing metal sleeve 2, the lower end of which is rolled as at 3 into interlocking engagement with the lower end of the body portion 1, the inturned edge 4 of the roll 3 being firmly forced or embedded into the fibrous body to secure a positive interlock and also a seal. The interconnection of the reinforcing metal sleeve 2 and the lower end of the body is enhanced and strengthened by forming an annular inwardly directed corrugation 5 in the sleeve 2 which correspondingly corrugates the part of the body portion which is engaged therewith.

A lower end head or bottom 6 is provided and adjacent its periphery is provided with a curved seat 7 which is, of course, annular and engages a portion of the corrugation 5 in the body portion whereby the seat 7 coats with the corrugation 5 in interconnecting the metal parts and the fibrous body portion. Below the seat 7 the lower end head has an outwardly directed annular ridge 8 which extends into the annular crotch between the end 4 of the roll 3 and the adjacent part of the fibrous body portion. Beyond the ridge 8 the lower end head is extended upwardly as at 9 and then inwardly as at 10 into firm interlocking engagement with the lower part of the sleeve 2 and with the lower half of the corrugation 5 thereof.

The upper part of the body portion is also surrounded by a reinforcing and strengthening metal member designated generally at 12. This metal member 12 is also, generally speaking, in the form of a sleeve or collar and has a portion 13 depressed inwardly to form the container

with a reduced upper end or neck. Above the inwardly dished or depressed portion 13 the metal member 12 is folded outwardly and downwardly providing an inclined flange portion 14, then extended vertically upwardly as at 15, then inclined upwardly and inwardly providing a flange portion 16 parallel to flange portion 14, and terminates in a rounded or crown-shape portion 17 which is firmly engaged and slightly embedded in the fibrous body of the container. The sleeve structure 12 thus has interlocking formations which securely interconnect it with the upper end of the container.

A removable metallic cover or closure 20 is provided and has a peripheral portion 21 designed to seat firmly against the inner surface of the upper end of the fibrous body and also overlap, to some extent, the crown portion 17 of the metal member 12. Integral with the peripheral portion of the cover is a downwardly and outwardly extending flange 22. Integral with and depending from the flange 22 is a vertical annular flange 23. Bendable fastening lugs 24 are integral with and depend from the lower edge of the flange 23 and terminate at their lower ends in hooks 25. Any suitable number of these fastening lugs are provided and they are spaced at intervals about the periphery of the flange 23 as will be understood from Figures 1 and 2.

The flange portion 16 of the metal member 12 provides a seat for a gasket 26 which, in the applied position of the cover, is compressed between this seat and the flange 22 of the cover to effect complete sealing of the container. When the cover is applied to the container the lugs 24 are straight as shown in Figure 3. To firmly secure the cover in position and hermetically seal the container the lugs are bent up under the shoulder provided by the flange portion 14 of the sleeve-like metal member 12. This not only secures the cover in position but compresses the gasket 26 between the flange 22 and the seat 16 so as to hermetically seal the container. The hooks 25 provide a convenient means whereby the hooks 24 can be straightened out in order that the cover may be removed.

It will be seen that as thus constructed the opening at the upper end of the container is provided with outwardly and downwardly extending flanges 16 and 14 which respectively provide a gasket seat and a locking shoulder. Cooperable with this structure is the downwardly and outwardly inclined flange 22 of the closure and the bendable lugs 24 thereof. These several parts are constituted of metal sufficiently resilient and bendable to preclude their fracture. Moreover, it should be noted that the lugs 24 are bent flush up into the angle between the locking shoulder 14 and the portion 13 of the reinforcing sleeve 12. As a result of these several features the closure is not only securely held to the container but the gasket 26 is compressed to provide a seal and this is done in such a way that even though the parts, when assembled, be distorted under the influence of shocks or blows the effectiveness of the seal will not be impaired. In fact, it will be enhanced.

The form of the invention shown in Figure 6 is identical with that just described except that the crown portion 17 of the metal member 12 is omitted. In this construction the seat for the gasket

26 is constituted in part by the portion 16' of the metal member and in part by the portion 16" of the container. Thus the gasket seals the juncture of the upper edge of the metal member 12 and the fibrous material.

The present invention also contemplates the provision of outwardly directed annular corrugations 27 in the reinforcing metal members or sleeves 12 and 2 at the upper and lower ends respectively of the container. Such corrugations 10 strengthen the construction and also provide a convenient means whereby the container may be rolled without danger or injury to its ends or to the means which connects the cover to the container.

While I have shown and described several constructions in which the invention may be advantageously embodied, it is to be understood that these constructions have been selected merely for the purpose of illustration or example and that various changes in the size, shape and arrangement may be made without departing from the spirit of the invention or the scope of the subjoined claims.

The invention claimed is:

1. A container comprising a body portion of fibrous material, a reinforcing metal sleeve structure surrounding the upper end of said body portion and having formations interlocked therewith, said interlocking formations including spaced 30 downwardly and outwardly inclined flanges, one providing a gasket seat and the other a locking shoulder, a gasket on said seat, a metallic closure for the upper open end of the container having a downwardly and outwardly inclined flange engageable with said gasket, and means cooperating with said closure flange and said shoulder for securing the closure in position and compressing the gasket between said flanges.

2. A container comprising a body portion of 40 fibrous material, a reinforcing metal sleeve structure surrounding the upper end of the body portion of the container and having formations interlocked therewith and providing an outwardly and downwardly inclined gasket seat and a locking shoulder below said seat, a gasket on said seat, a removable metallic closure for the upper end of the container having a downwardly and outwardly inclined flange engageable with said gasket, and bendable securing lugs integral with the 50 closure and adapted to be bent up under the shoulder to secure the closure to the container and compress the gasket between said flanges.

3. A container comprising a body portion of fibrous material, a reinforcing metal sleeve structure surrounding the upper end of said body portion and having formations interlocked therewith, said interlocking formations of the sleeve structure including spaced downwardly and outwardly inclined flanges, one providing a gasket seat and the other a locking shoulder, a gasket on said seat, a metallic closure for the upper open end of the container having a downwardly and outwardly inclining flange engageable with said gasket, the said inclining flange of the formation providing a gasket seat having an integral extension extending over and imbedded in the upper portion of the fibrous body, and means cooperating with said closure flange and said shoulder for releasably securing said closure in position and compressing the gasket between the flanges.

ALFRED J. CHAMBERLAIN.
